CONTAINER UNIT FOR DISINFECTANTS, DEODORANTS, INSECTICIDES, AND THE LIKE

David Rauch, Lancaster, Mass., assignor to Van
Brode Milling Co., Inc., Clinton, Mass., a cor-
poration of Massachusetts

Application February 16, 1953, Serial No. 23,628

Term of patent 14 years

(Cl. D16—2)

To all whom it may concern:

Be it known that I, David Rauch, a citizen of the United States, residing at Lancaster, Commonwealth of Massachusetts, have invented a new, original, and ornamental Design for a Container Unit for Disinfectants, Deodorants, Insecticides, and the like, of which the following is a specification, reference being had to the accompanying drawing, forming part hereof.

Fig. 1 is a front elevation of a container unit for disinfectants, deodorants, insecticides, and the like, showing my new design;

Fig. 2 is a rear elevation thereof;

Fig. 3 is a side elevation of the same; and

Fig. 4 is a section taken on line 4—4 of Fig. 1, on a larger scale.

I claim:

The ornamental design for a container unit for disinfectants, deodorants, insecticides, and the like, as shown.

DAVID RAUCH.
